UNITED STATES PATENT OFFICE.

FRANK LAUSCHER, OF POWERS, MICHIGAN.

GRAVEL SHAKER.

Application filed November 26, 1923. Serial No. 677,034.

To all whom it may concern:

Be it known that I, FRANK LAUSCHER, a citizen of the United States, residing at Powers, in the county of Menominee and 5 State of Michigan, have invented certain new and useful Improvements in Gravel Shakers, of which the following is a specification, reference being had to the accompanying drawings.

10 This invention relates to devices for shaking and sifting granular material, particularly gravel, and has for its object the provision of a novel power driven machine for this purpose which will efficiently operate 15 to sort or sift gravel in a very rapid manner, the result being that a uniform grade or grades of material may be had.

An important object is the provision of a device of this character which is so constructed as to be readily portable whereby it 20 may be easily conveyed from place to place where its use is desirable, it being unnecessary to disassemble the mechanism for the purpose.

25 Another, and more specific object is the provision of a machine of this character which is so constructed that its base portion serves as a species of bin within which sifted material accumulates, the pieces of excessive 30 size being discharged outwardly beyond one end of the device so that danger of accidental remixing will be avoided.

An additional object is the provision of a device of this character which will be simple and inexpensive to manufacture, easy to 35 operate and control, positive in action, efficient and durable in service, and a general improvement in the art.

With the above and other objects and advantages in view, the invention consists in 40 the details of construction to be hereinafter more fully described and claimed, and illustrated in the accompanying drawings in which:

45 Figure 1 is a side elevation of the device;
Figure 2 is a front end view;
Figure 3 is a vertical section; and
Figure 4 is a horizontal section on the line 4—4 of Figure 1.

50 Figure 5 is a detail section on the line 5—5 of Figure 3.

Referring more particularly to the drawings I have shown my device as comprising 55 an upright frame which may be constructed of wooden beams or bars or of angle bars of any desired cross sectional configuration.

This frame is shown as consisting of longitudinal and transverse bottom sills 10 and 11 respectively, suitably secured at the lower ends of and supporting upright corner posts 12 which are connected by cross bars 13 and diagonally arranged brace bars 14, all of which are located at the extreme upper ends of the posts. Secured to the corner posts at the inner sides thereof and extending longitudinally of the frame are bars 15 which are preferably braced by means of diagonal brace bars 16 secured thereto at points spaced from the ends and also secured to the corner posts at the upper and intermediate 70 portions thereof as clearly indicated in Figure 1. It is also preferable to provide one side of the machine with a diagonal brace 17 which is secured to one corner post at its intermediate portion and which is also secured 75 to the upper end of the other corner post at the same side of the frame. Obviously, if found necessary, more braces may be provided where needed and if desired some of those disclosed might be omitted in some instances, especially if the frame be constructed of angle iron.

Secured to the corner posts at one side of the machine are boards or planks 18 which extend upwardly to a point substantially intermediate the ends of the posts, and secured to these same posts and also to the opposite posts are transversely arranged boards 19 which extend upwardly to substantially the same point as the longitudinal boards 18. 80 By this construction it will be seen that the space defined within the frame by the boards 18 and 19 constitutes a species of storage bin within which the sifted material accumulates.

Located within the confines of the frame and above the closed-in side and ends defined by the boards 18 and 19 respectively is a rectangular frame 20 having any desired specific construction but here represented as 100 including longitudinal bars 21 connected by cross bars 22 and slats or cleats 23 secured to the undersides of the longitudinal bars. This frame 20 is mounted for oscillatory movement and is therefore suspended from 105 the bars 15 by means of pivoted hangers 24. The mounting is such that the frame 20 may swing longitudinally but not transversely. The bottom of this movable frame is provided with a screen 25 of suitable mesh depending upon the fineness of the sifting desired.

Secured upon the top of the movable frame is a box like structure 26 which has one side 27, higher than the other 28 and formed of sections 29 and 30. Within the 5 box are transversely arranged laterally inclined grate bars 31 engaged at one end between the sections 29 and 30 and having their other ends secured upon the side 28. It might be mentioned in passing that the 10 ends 32 and 33 of this box like structure are reinforced by longitudinally extending stay rods 34 and that braces 35 may be provided secured to the end 32 and to the longitudinal bars 21.

15 The operating means for the shaker or movable frame comprises a shaft 36 extending transversely of the main frame at the lower end of the movable frame and journaled in suitable bearings 37 carried by two 20 corner posts. This shaft is shown as equipped with a pulley 38 to which power may be applied by any suitable means for the purpose of operating the mechanism. The central portion of the shaft is formed 25 with a crank 39 upon which is engaged a bar 40 which constitutes a pitman, the bar being equipped with a bearing 41 for the crank. This bar or pitman extends longitudinally above the movable frame 20 and is 30 pivotally connected at 42 with a cross bar 43 forming part of the movable frame 20.

In the operation, it is evident that when 35 the shaft 36 is rotated the entire frame 20 will be swung or oscillated back and forth, the hangers 24 permitting this movement. Material to be shaken or sifted is shoveled or otherwise dumped into the box 26 and it is evident that large rocks cannot pass 40 through between the grate bars, while at the same time these bars will operate to break up any lumps which are not solid stone. The material which passes between these grate bars drops onto the wire screen 45 and some of it, the fine matter, passes through the screen and accumulates within the bin like bottom of the device, the coarse pieces being discharged from the screen at the lower end thereof and falling outwardly beyond the bin so as to be incapable of mixing 50 with the fine material within the bin. Quite naturally the end 32 of the box 26 does not contact with the screen as it is essential that a space be provided for permitting the material on the screen to slide downwardly 55 therealong during the shaking or agitating movement imparted to the entire movable frame by means of the crank and pitman connection.

60 From the foregoing description and a study of the drawings it will be apparent that I have thus provided a simply con-

structed and very inexpensive sifting or sorting device for gravel or other material and one which is readily portable so that it will be well adapted for use on the farm as 65 well as by contractors and builders and at gravel pits. The operation is bound to be rapid and the device will consequently be a great time and labor saver so that it should recommend itself to those having occasion 70 to employ its services.

While I have shown and described the preferred embodiment of the invention it is, of course, to be understood that I reserve the right to make such changes in 75 the form, construction and arrangement of parts as will not depart from the spirit of the invention or the scope of the subjoined claims.

What I claim is:—

1. A shaking machine of the character described comprising a stationary supporting frame including corner uprights and cross bars connecting the same, longitudinal bars connecting said uprights, a side wall secured 85 to the uprights at one side, an end wall secured to the uprights at one end to define an accumulation bin, an inclined frame having its bottom slatted and covered with wire screen, hangers pivotally suspended from 90 said longitudinal bars and pivotally connected with said inclined frame for permitting longitudinal oscillatory movement thereof, a crank shaft journaled on the uprights at one end, a pitman pivotally connected with said inclined frame and connected with the crank shaft, and a hopper 95 mounted on the inclined frame and having a grate-like bottom.

2. A machine of the character described 100 comprising a stationary frame having its lower portion closed except at one side whereby to define an accumulation bin, a movable frame mounted within said stationary frame and supported by pivoted 105 hangers whereby to be capable of longitudinal oscillatory movement, said movable frame being provided with a wire screen covering the entire bottom thereof, crank and pitman means mounted on the stationary frame and connected with said movable frame for effecting swinging thereof, and a box like hopper receptacle carried by said movable frame and provided internally with grate bars, the side of the receptacle 110 above the closed in side of the main frame being higher than the other side and said grate bars being correspondingly inclined.

115 In testimony whereof I hereunto affix my signature.

FRANK LAUSCHER.
